(57) **CLAIM**

We claim the ornamental design for a foam nozzle, as shown and described.

DESCRIPTION

FIG. 1 is a perspective view from the top of an embodiment of a foam nozzle, showing our new design;

FIG. 2 is a perspective view from the bottom thereof;

FIG. 3 is a front elevation view thereof;

FIG. 4 is a left-side elevation view thereof;

FIG. 5 is a rear elevation view thereof;

FIG. 6 is a right-side elevation view thereof;

FIG. 7 is a top plan view thereof; and,

FIG. 8 is a bottom plan view thereof.

The broken lines shown in the figures are included for the purpose of illustrating environment and form no part of the claimed design.
